Inventor:
Peter Clifton Holmquist.
By: *Wm. F. Bell*
Atty.

UNITED STATES PATENT OFFICE.

PETER CLIFTON HOLMQUIST, OF CHICAGO, ILLINOIS.

CURTAIN STRETCHER.

Application filed October 4, 1920. Serial No. 414,425.

To all whom it may concern:

Be it known that I, PETER CLIFTON HOLMQUIST, a citizen of the United States, residing at Chicago, in the county of Cook 5 and State of Illinois, have invented certain new and useful Improvements in Curtain Stretchers, of which the following is a specification.

This invention relates to curtain stretchers but more particularly to such as are intended to be supported in a substantially upright position and has for its primary object to provide a structure which is light in weight, strong, easily assembled and adjusted and in which the parts are so joined that the distortion frequently occurring in frames of this type is obviated.

Further objects of the invention are to provide an improved corner clamp for binding together the members of the frame, and to provide a simple and rigid hinge for connecting the legs or supports to the stretcher frame.

Referring to the drawings:

Fig. 1 is a front view of a curtain stretcher with the selected embodiment of my invention incorporated therein.

Fig. 2 is a side elevation.

Fig. 3 is a detailed perspective view of a portion of the invention, the parts being in disassembled position.

Fig. 4 is a detailed perspective view of the corner clamp.

In the drawings the selected embodiment of the invention is shown to comprise a frame consisting of side pieces 5 and end pieces 6 secured together at the corners. The upper extremities of the end pieces 6 abut the inner edge of the corresponding side piece 5 and plates 7 and 8 are secured to and project beyond such extremities on opposite sides thereof. The plates 7 have their upper extremities turned inwardly to form flanges 9 to enter the longitudinal slot 10 in the side piece. The outer extremities of the plates 8 are formed flat and fit the rear face of the side piece. Binding bolts 11 pass through the plates 7 and 8 and the upper end portion of the end pieces.

The opposite ends of the lower side pieces 5 project over the corresponding portions of the end pieces 6 and these pieces are bound together by corner clamps 12. Each of these corner clamps comprise a broad base plate 13 having a lug 14, a binding bolt 15,

and a broad hook shaped portion 16 formed integral therewith. The lug 14 is preferably long and fits within a longitudinal slot 17 in the lower end portion of the end piece 6. The bolt 15 passes through the slot 17 and a thumb nut 18 is provided to bind the clamp to the end pieces. The inwardly turned extremity 19 of the hooked shaped portion 16 of the clamp fits within the longitudinal groove 20 in the lower side piece 5 to bind the end and side pieces together. Distortion of the frame is prevented by the long lug 14 and the broad inturned extremity 19 of the clamp.

Hooks 21 to engage the edges of the curtain are spaced longitudinally of the end and side pieces at desired intervals. These are shown mounted in longitudinal slots 22 in the side and end pieces to permit adjustment but the particular type of hook and method of mounting the same form no part of the present invention and any of the well known types of curtain engaging means might be used.

In order to support the frame in substantially a vertical position to facilitate drying of the curtain, supporting legs 23 are mounted on each of the end pieces and are hingedly connected thereto. While any of the well known types of hinge might be used upon the legs, the lightness of the frame and its length renders it necessary to provide a hinge joint which is particularly substantial or twisting action is certain to occur. I have provided a hinge connection which is simple, light, strong and which will not permit of twisting of the frame relative to the supports or legs. This hinge comprises a plate 24 having a pair of prongs or spurs 25 struck therefrom to enter corresponding perforations 26 in the plate 8, and the side portions of plate 24 are bent outwardly to form ears 27 extending at substantially a right angle to the central portion of the plate and adapted to fit the corresponding side faces of the support or leg 23. A rivet 28 passes through the plates 7, 8, and 24 and the end piece 6 to bind these parts together and retain the prongs 25 within the perforations 26.

These prongs prevent rotation of the plate 24 on the rivet 28. The outwardly turned ears 27 of the plate 24 are provided with oppositely disposed perforations 29 to receive a hinge pin 30 which passes through 110

the upper end portion of the support or leg 23. The upper end of the support 23 is bevelled at 31 preferably at an angle of about 45° so that when the support is swung outwardly into the position indicated in the solid lines in Fig. 2 of the drawing, this inclined face will seat itself against the outer face of the plate and thus prevent further outward swinging of such support.

10. While the contacting of the bevelled end of the support with the face of the plate as described would generally be sufficient to prevent the support from swinging outwardly too far, I find it advantageous to provide a 15 catch 32 which is in the present embodiment pivoted at one end on the end piece 6 and has a lateral slot 33 near its opposite end to admit the screw or pin 34 in the support.

20. These curtain stretching frames are frequently made 6 feet or more in length depending on the size of curtains to be handled and it is necessary that they be of light weight in order that they may be readily moved about. Likewise it is essential that they be easily assembled adjusted and taken apart as occasion may require. Great difficulty has always been encountered in so connecting the members forming the frame 25 that this frame would not become distorted and thus improperly shape the curtain being stretched thereon. The clamps 12 are provided with wide flanges which fit closely in slots in the parts to be joined so that 30 when these clamps are drawn into place by the tightening of the thumb nut on the binding bolt, no distortion is possible. The corner clamps can be made at a very low cost by thus forming the flanges and binding bolts integral with the base plate for 35 no tapping of holes is necessary and the entire structure is much more strong than would be the case if it were formed of numerous separate parts.

40. The hinge connection hereinbefore described would normally be made out of pressed metal and requires only one rivet or binding pin to secure it to the frame. It is 45 neat in appearance and renders relative twisting of the frame and supports or legs 50 impossible. In order to permit the supporting leg to be readily detached from the frame I find it advantageous to use a cotter pin as a pivot for the hinge but any other

suitable form of pin or bolt might be substituted therefor. 55

I am aware that changes in the form and proportion of parts and in the details of construction may be made without departing from the spirit or sacrificing the advantages of the invention and I therefore reserve the right to make all such changes as fairly fall within the scope of the appended claims. 60

I claim:

1. A curtain stretcher comprising a frame, supporting legs therefor, and a hinge connection between said frame and each of said legs including a perforated base plate secured to said frame, a hinge plate secured to said base plate and provided with prongs struck therefrom to rest within the perforations in said base plate, a pair of ears formed on said hinge plate to fit the corresponding side faces of the upper extremity 75 of said leg, and a hinge pin passing through said ears and said leg.

2. A curtain stretcher comprising side pieces having longitudinal slots, end pieces having longitudinal slots, and clamps to secure the side and end pieces together each including a base plate of greater width than the slot in said end piece and resting on said end piece over said slot, a flange on said plate fitting within the slot in said end piece, 80 and a binding bolt integral with said base plate and passing through said end piece, said plate having a broad extension projecting over said side piece and its extremity resting within and fitting the slot in said 90 side piece.

3. A curtain stretcher comprising side pieces having longitudinal slots, end pieces having longitudinal slots, and clamps to secure the side and end pieces together each 95 including a base plate of greater width than the slot in said end piece and resting on said end piece over said slot, a flange on said plate fitting within the slot in said end piece, and a binding bolt formed on said flange and projecting through the slot in said end piece, said plate having a hook shaped extension projecting up at the rear edge of the side piece and over the top thereof and having a broad flange formed on its outer extremity fitting within the slot in said side piece. 100 105

PETER CLIFTON HOLMQUIST.
